CLAIM

I claim the ornamental design for a shoelace clip, as shown and described.

DESCRIPTION

FIG. 1 is a perspective view of a shoelace clip, showing my new design;

FIG. 2 is a rear elevational view of the shoelace clip of FIG. 1;

FIG. 3 is a front elevational view of the shoelace clip of FIG. 1;

FIG. 4 is a left side elevational view of the shoelace clip of FIG. 1;

FIG. 5 is a right side elevational view of the shoelace clip of FIG. 1;

FIG. 6 is a top plan view of the shoelace clip of FIG. 1; and,
FIG. 7 is a bottom plan view of the shoelace clip of FIG. 1.
